UNITED STATES PATENT OFFICE

110,898

DESIGN FOR A TURN SIGNAL

Fritz Katzky, Chicago, Ill.

Application May 31, 1938, Serial No. 77,469

Term of patent 14 years

To all whom it may concern:

Be it known that I, Fritz Katzky, a citizen of the United States, residing at Chicago, county of Cook, State of Illinois, have invented a new, original, and ornamental Design for a Turn Signal, of which the following is a specification, reference being had to the accompanying drawing, forming a part thereof.

Figure 1 is a perspective view of a turn signal showing my new design, the same being shown in its closed position; and

Figure 2 is a perspective view showing the turn signal in open or signal-indicating position.

In the drawing, I have illustrated only one side of a turn signal showing my new design, but it is to be understood that the other side thereof is substantially the same in appearance as the side actually shown.

I claim:

The ornamental design for a turn signal, as shown and described.

FRITZ KATZKY.
